CLAIM

We claim the ornamental design for a pad of labels, as shown and described.

DESCRIPTION

FIG. 1 is a top perspective view of a pad of labels showing our new design.

FIG. 2 is a top plan view of the pad of labels of FIG. 1.

FIG. 3 is a bottom plan view of the pad of labels of FIG. 1.

FIG. 4 is a front-edge elevational view of the pad of labels of FIG. 1.

FIG. 5 is a back-edge elevational view of the pad of labels of FIG. 1.

FIG. 6 is a left-side elevational view of the pad of labels of FIG. 1.

FIG. 7 is a right-side elevational view of the pad of labels of FIG. 1.

FIG. 8 is a top perspective view of pad of labels of FIG. 1 with the flap in an open position.

FIG. 9 is a top plan view of the pad of labels of FIG. 8.

FIG. 10 is a bottom plan view of the pad of labels of FIG. 8.

FIG. 11 is a right-side elevational view of the pad of labels of FIG. 8.

FIG. 12 is a left-side elevational view of the pad of labels of FIG. 8.

FIG. 13 is a front-edge elevational view of the pad of labels of FIG. 8.

FIG. 14 is a back-edge elevational view of the pad of labels of FIG. 8; and,

FIG. 15 is a top perspective view of the pad of labels shown with the flap in a partially opened position.

In the drawings, the broken lines represent perforations.

1 Claim, 7 Drawing Sheets
